UNITED STATES PATENT OFFICE.

WILLIAM H. SAUVAGE, OF NEW YORK, N. Y., ASSIGNOR, BY MESNE ASSIGNMENTS,
TO GOULD COUPLER COMPANY, OF NEW YORK, N. Y.

SLACK ADJUSTER.

Refiling of abandoned application Serial No. 307,124, filed June 27, 1919. This application filed April 18, 1922. Serial No. 555,223.

To all whom it may concern:

Be it known that I, WILLIAM H. SAUVAGE, a citizen of the United States, residing at New York, in the county of New York and State of New York, have invented new and useful Improvements in Slack Adjusters, of which the following is a specification.

This invention relates to slack adjusters 10 for railway brake systems and more particularly to what is known as automatic slack adjusters especially designed for taking up the excess slack in the brake rigging of railway vehicles.

One of the objects of the present invention is to provide an automatically operated slack adjuster of a simple and practical design particularly adapted for use in connection with the foundation brake rigging of 20 cars although with slight modification, various features are applicable to slack adjusters in other locations as well.

Another object is to provide a slack adjuster of the above general type adapted 25 automatically to take up and hold all of the slack on excess travel of the brake rigging during a single application of the brakes, in contradistinction to devices now in use in which the slack is only partially 30 taken up on application or is taken up on release of the brakes.

A further object is to provide a slack adjuster having relatively few parts which may be inexpensively manufactured and assembled yet be reliable and efficient in use 35 and operation.

A further object is to provide an improved slack adjuster of the last above mentioned type adapted to insure uniform piston travel at all times and to take up and hold the entire excess slack of the brake rigging on or during a single application of the brakes.

Other objects will be in part obvious from 45 the annexed drawings and in part indicated in connection therewith by the following analysis of the invention.

This invention accordingly consists in the features of construction, combination of 50 parts and in the unique relations of the members and in the relative proportioning and disposition thereof, all as more completely outlined herein.

Drawings depicting one of several de-

sired forms have been annexed as a part 55 of this disclosure, and in such drawings like characters of reference denote corresponding parts throughout all of the views, of which—

Figure 1 is a semi-diagrammatic plan 60 view of such parts of the foundation brake rigging, with the invention applied thereto, as may be necessary to fully understand the same; and

Figure 2 is an enlarged detail view, partly 65 in section, showing the slack adjuster.

Referring now to the drawings in detail and more particularly to Figure 1, 5 denotes the main cylinder of the foundation 70 brake rigging usually mounted beneath the floor of the car and having an air reservoir 6, a triple valve 7 and an inlet or supply pipe 8. This cylinder 5 is provided with a piston 10, piston rod 11 connected to one end of a live lever 12, the opposite end of 75 which lever is provided with a pull rod 13 leading to the brake rigging mounted on the truck. A chain 14 connected at one end to rod 11 is adapted to be connected to the hand brake mechanism at its other end. 80 The central part of the live lever 12 is connected by means of a rod or link 15 with the central part of a dead lever 16. One end of this lever 16 connects with a pull rod 17 leading to the brake rigging mounted 85 on the truck at the opposite end of the car while the opposite end of the dead lever is mounted in a recess portion 18 in a movable rod 20 as shown more clearly in Figure 2. 90

It will, of course, be understood that the mechanism above described with the exception of the last connection of the dead lever 16, is of old and well known construction 95 and arrangement in foundation brake rigging, the parts being so connected that as the piston 10 moves outwardly the live and dead levers with the intervening link 15 will be moved to actuate the brakes on each truck. As the wear in the parts develop, or 100 the brake shoes wear down, the normal piston travel increases until finally a point is reached whereby it is impossible to properly apply the brakes and accidents may result.

It is accordingly, as previously stated, one 105 of the objects of this invention to apply a more reliable and efficient slack adjuster to the brake rigging whereby uniform piston

travel is insured at all times and the proper application of the brakes may be depended upon.

The present mechanism embodies a relatively short cylinder 21, Figure 2, provided with a piston 22 behind which air is adapted to be admitted through pipe 23 communicating with a port 24 in the main cylinder 5. A suitable cock 25 is provided to close the pipe 23, if desired, at any time. It will thus be seen that when the piston 10 exceeds its predetermined piston travel and uncovers the port 24, air will be admitted through the pipe 23 and move the piston 22 relatively towards the right against the action of a spring 26 coiled within a chamber 27.

This piston 22 is provided with a sleeve 28 and preferably having formed integrally therewith is a housing 30 carrying a plurality of holding dogs 31. These dogs are generally of rectangular shape having openings therein through which the combined take-up and holding rod 20 is adapted to pass. They are normally held in canted position, as shown, by means of a coiled spring 32 surrounding the rod.

Secured to the under side of the car body is a bracket 33 provided with a housing 34 within which is a second holding dog 35 similar to the dogs 31 and also held in canted position by means of spring 36. Both housings are provided with release levers 37 of any desired type whereby when moved towards the right hand position they will straighten out the dogs to a plane normal to the axis of the rod 20 thus permitting the rod 20 to be moved freely in either direction.

The operation of the present device is substantially as follows:

When the normal travel of the piston 10 exceeds a predetermined amount to properly apply the brakes the port 24 is uncovered allowing air to pass through the pipe 23 to the back of the piston 22. This forces the piston 22 relatively towards the right, compressing the spring 26, and by reason of the dogs 31 which have a biting engagement with the rod 22, the fulcrum point of the lever 16 is carried relatively towards the right, the opposite or right hand end of the rod 20 passing freely through the dog 35. On release of the brakes the piston 10, of course, returns to normal position under the usual release spring and the spring 26 will force the piston 22 back to normal position, as shown in Figure 2. The rod 20, however, will be held in its new position by the dog 35, the casing 30 returning with the piston 22, thereby sliding the dogs 31 along the rod 20 an amount corresponding to the slack taken up. In this manner, the entire slack will be taken up and held on or during a single application of the brakes and if at any time the brakes should be on for a relatively

long period, as when coasting down a mountain, for instance, and an unusual wear on the brake shoes takes place the slack will be taken up as may be necessary whenever the normal piston travel is exceeded.

It will thus be seen that the present invention provides a simple and practical slack adjuster mechanism, in which the adjusting rod and take up rod are combined in one, thus simplifying the mechanism as a whole and reducing the number of parts to be manufactured and assembled. In short, the invention is believed to accomplish, among others, all of the objects and advantages herein set forth.

I claim:

1. In an automatic slack adjuster, in combination, a source of power including piston, permanent and temporary take up and holding means, and a single rod coacting with both of said means and adapted therewith to take up and hold all of the excess slack caused by excess travel of the piston on application of the brakes.

2. In an automatic slack adjuster, in combination, a source of power including a piston, permanent and temporary take up and holding dogs, a single rod associated and coacting therewith, and means for moving said rod actuated by said source of power thereby to take up and hold all of the excess slack caused by excess travel of the piston on application of the brakes.

3. In an automatic slack adjuster, in combination, a source of power including a piston, permanent and temporary take up and holding dogs, a single rod associated therewith, and means for moving said rod actuated by said source of power and adapted to take up and hold all of the excess slack caused by excess travel of the piston on application of the brakes, said means being actuated only on excess travel of the piston of said source of power.

4. In a brake system, in combination, an air brake cylinder and piston having a port adapted to be uncovered on excess piston travel, and a pneumatically actuated slack adjuster adapted to be operated on excess piston travel to take up all of the excess slack on application of the brakes, said slack adjuster including a piston rod and a single combined holding, take up and adjusting rod.

5. In a brake system, in combination, an air brake cylinder having a port adapted to be uncovered on excess piston travel, and slack adjuster mechanism adapted to be operated on excess piston travel to take up all of the excess slack on application of the brakes, said slack adjuster comprising a piston rod and a combined take up and adjusting rod telescoping therewith.

6. In a brake system, in combination, an air brake cylinder having a port adapted to be

uncovered on excess piston travel, and a pneumatically actuated slack adjuster adapted to be operated on excess piston travel to take up all the excess slack on application of the brakes, said slack adjuster comprising a piston and a combined holding, take-up and adjusting rod, and alternately operating means adapted to engage said rod to move the same in one direction and to hold it against movement in the opposite direction.

7. In a brake system, in combination, an air brake cylinder having a port adapted to be uncovered on excess piston travel, and a pneumatically actuated slack adjuster adapted to be operated on excess piston travel to take up and hold all of the excess slack on application of the brakes, said slack adjuster comprising a piston, a combined holding, take up and adjusting rod, and alternately operating means adapted to engage said rod to move the same in one direction and hold it against movement in the opposite direction, said means including two sets of dogs normally held in canted relation to said rod.

8. In a brake system, in combination, an air brake cylinder having a port adapted to be uncovered on excess piston travel, and a pneumatically actuated slack adjuster adapted to be operated on such excess piston travel to take up and hold all of the excess slack on application of the brakes, said slack adjuster comprising a cylinder having a piston and a two-part telescopic piston rod, one of said parts being provided with a housing having holding means therein adapted to co-act with and engage the other of said parts on movement of the piston in one direction and to permit relative movement of said parts on opposite movement of the said piston.

9. In a brake system, in combination, an air brake cylinder having a port adapted to

be uncovered on excess piston travel, and a pneumatically actuated slack adjuster adapted to be operated on excess piston travel to take up and hold all of the excess slack on application of the brakes, said slack adjuster including a cylinder, a piston and a two-part telescopic piston rod, one of said parts being provided with a housing having means adapted to co-act with and engage the other of said parts on one movement of the piston and to permit relative movement of said parts on opposite movement of the piston, and separate and independently operating means adapted to coact with the telescoping part of the piston rod to prevent movement thereof on return of the piston head to normal position.

10. In a brake system, in combination, an air brake cylinder having a port adapted to be uncovered on excess piston travel, and a pneumatically actuated slack adjuster adapted to be operated on excess piston travel to take up and hold all of the excess slack on application of the brakes, said slack adjuster comprising a cylinder having a two-part telescopic piston rod, and a piston, one of said parts being provided with a housing having holding means adapted to co-act with and engage the other of said parts on movement of the piston and to permit relative movement of said parts on inward movement of the piston, and separate and independently operating holding means adapted to coact with the telescoping part to prevent inward movement thereof on return of the piston head to normal position, and means for releasing both of said holding means whereby said telescoping part of the piston rod may be freely moved in either direction.

In witness whereof I have hereunto set my hand this 7th day of April, 1922.

WILLIAM H. SAUVAGE.
